AUTO SIGNALING DEVICE

Filed Sept. 14, 1931

UNITED STATES PATENT OFFICE

2,008,849

AUTO-SIGNALING DEVICE

Leo J. Binder, Spokane, Wash.

Application September 14, 1931, Serial No. 562,725

2 Claims. (Cl. 116—50)

My invention relates to auto-signaling devices and is also adapted to be used as an auto-pass or parking signal. Certain objects of the invention are to provide a signal device, in combination with a motor vehicle, comprising a plurality of tubes telescopically arranged and provided with automatic means whereby the device is readily extended to the outward operative position and retracted to the inward inoperative position by the driver from the seat of the vehicle. Further objects are to provide lighting means and reflector means for the extendible tubular members together with a fabric or flexible stocking forming an envelope around the tubes in the outward position and adapted to fold within the device in the inward position, and whereby part of the light is projected rearwardly into the stocking or envelope in its outstretched position. Still further objects are to provide a conduit that is arranged to serve the dual purpose of supplying current to the light and as a means for retracting the device to the inoperative position.

With the above and other objects in view which will appear as the description proceeds, the invention consists of the novel construction, adaptation, combination and arrangement of parts hereinafter described and claimed. These objects are accomplished by devices illustrated in the accompanying drawing; wherein:—

Figure 1 is a general view showing the device in elevation in the outward position and mounted on the cowl portion of an automobile which is shown in transverse vertical section;

Fig. 2 is an enlarged view in longitudinal section showing the device in its retracted position;

Fig. 3 is a view in transverse vertical section taken substantially on a broken line 3—3 of Fig. 2;

Fig. 4 is a fragmentary detail view in perspective showing a portion of the inner tube with slots for retaining the light bulb and reflector;

Fig. 5 is a view in longitudinal section showing a modified form of device in its extended position and adapted to be operated by a pressure medium and spring arrangement and

Fig. 6 is a fragmentary detail view in longitudinal section showing the means for mounting the light bulb and spider member on the inner tube.

Referring to the drawing throughout which like reference numerals indicate like parts, the numeral 5 designates the cowl of the forward portion of a motor vehicle. A hole is provided through the right or left hand side of said portion and a bracket plate 6 is secured thereto with an internally threaded projecting neck registering with the hole. An outer tubular member 7, threaded its full length, is screwed into said neck and is provided on its outer end with a flared or enlarged bowl portion 8. Said outer tube is pro-

vided near its outer end with an internal annular shoulder 9. An intermediate tube 10 is telescopically mounted within said outer tube and is provided near its inner end with an external annular shoulder 11 that is adapted to abut against the said internal shoulder 9 when said tube is in its outwardly extended position. The inner end of the outer tube is threadedly provided with a cap 12 and a coiled spring 13 interposed therein between said cap and the inner end of the intermediate tube is adapted to normally retain said intermediate tube in the extended position.

An inner tube 14 is telescopically mounted within the intermediate tube 10 projecting exteriorly thereof and a spring 15 coiled around its projecting end portion and bearing against the outer end of said intermediate tube is arranged to normally retain said inner tube in the outwardly extended position. As shown in detail in Fig. 4, the outer end portion of the inner tube is provided with longitudinal diametrically opposite slots 16 one or both of which are provided with offset slot portions 17 at their inner ends. A light bulb 18 has small projections 19 on its neck 20 which slide into said slots and are turned into their offset portions to retain the bulb in position. Said slots are also provided with intermediate offsets 21.

An annular spider member 22 has small interior projections 23 arranged to slip into the slots 16 of the inner tube 14 and be turned into the offsets 21 whereby the spider member is held in position as most clearly shown in Fig. 3 of the drawing. The exterior portion of said spider is threaded to receive the internally threaded portion of an annular reflector member 24. Said reflector is provided with an inner concave portion 25 that envelops a portion of the bulb 18 and is thus adapted to reflect a portion of the light from the bulb inwardly, and an outer flange portion 26 that is arranged to reflect some of the light outwardly. Said flange portion is provided with a rim 27 that is adapted to receive a globe 28 of red glass or other suitable material and U-shaped wires 29, fitting into grooves in said globe, have their ends secured to said rim thus retaining the globe in position and serving as guards for the globe.

The outer enlarged bowl portion 8 of the outer tube 7 is internally threaded to receive an annular visor or shield 30 whose interior end portion is bent to provide an annular groove 31. An envelope or stocking 32 that is preferably made of red rubberized silk has one of its ends disposed within said groove and a spring snap ring 33 retains said end securely in the groove. The other end of said envelope is secured between the spider member 22 and the reflector 24 when they are screwed together as will be understood. Said envelope is accordion pleated so that it folds neatly

within the bowl 8 when the device is in the retracted position as shown in Fig. 2, and provides a smooth covering for the tubes when the device is in the extended position as shown in Figs. 1 and 5.

Electric energy is supplied to the light bulb 18 by means of a heavily insulated cable 34 whose outer terminal has a brass bushing 35 thereon and is secured in engageable relation with the terminal of said bulb by means of a screw 36 in a hard rubber plug 37 slidably mounted in the outer end portion of the inner tube 14. Another plug 38 is mounted within the central portion of said inner tube against shoulders 39 that are punched inwardly from the metal thereof. Said cable passes centrally through said plug and is held therein by set screws 40. A coiled spring 41 interposed between said two plugs serves to hold the cable terminal in contact with the terminals of the light bulb. Any slack in this portion of the cable may be eliminated by means of adjustment of the set screws as will be understood.

The cable 34 serves the dual purpose of supplying current to the lamp 18 and acts as a means for retracting the intermediate and inner tubes 10 and 14 respectively. Said cable extends exteriorly of the inner tube through a male and female sleeve arrangement 42 on the end cap 12 slidably into a thin extension tube 43. The remote end of said extension tube is connected to the operating cylinder 44 which is mounted by means of bracket clamps 45 on the steering post 46 of the motor vehicle as shown in Fig. 1. The remote end of the cable, passing through said extension tube, is connected to a lever 47 within said operating cylinder. Said lever may project out through a slot extending the full length of said operating cylinder whereby same may be slidably moved up and down. In the extreme lowered position said lever contacts with a cap 48 on the bottom of the operating cylinder thus closing the circuit and causing the bulb 18 to light, and in the extreme raised position the lever may be caught in a notch at the top of the operating cylinder thus retaining the cable together with the inner and intermediate tubes 14 and 10 in the retracted position against the tensioned springs 13 and 15. In this retracted position the light bulb will show clear of the vehicle windshield 49 and thus may be used as a pass or parking light. For this purpose a switch button arrangement 50 may be provided on the upper end of the operating cylinder whereby the circuit may be closed for the light bulb when same is in the retracted position.

In the outward or operative position of the device the springs 13 and 15 project the tubes 10 and 14 outwardly to the full extent and the fabric envelope 32 forms a chamber around the tubes. The reflector portion 25 directs some of the light from the bulb 18 back through the spider member 22 into said envelope. The envelope is thus illuminated and, together with the light from the globe 28, provides a very efficient and distinctive signal for auto-vehicles.

In the modified form shown in Fig. 5 of the drawing I have shown means whereby the device may be operated a pressure medium such as compressed air or oil under pressure. In this case the central conduit 34 is eliminated and the extension tube 43 supplies the pressure medium to

the outer tube 7. The pressure medium thus causes the inner tube 14 to move outwardly carrying the bulb 18 and the envelope 32 to the extended position by means of a connecting rod 51. Said rod is insulated from the bulb and current is supplied to the bulb by a conduit 53 and returns to said rod from the socket of the bulb through a short ground wire 54. The pressure medium may be controlled by a suitable valve arrangement and upon release of the pressure a return spring 52 carries the device back to the normally retracted position.

Having thus described my invention, it being understood that minor changes in its construction and arrangement may be resorted to without departing from the scope and spirit of the invention, what I claim and desire to secure by Letters Patent of the United States is:—

1. An auto-signaling device comprising an outer tube having an enlarged bowl end portion, a plurality of tubes telescopically mounted for slidable movement into the outer tube, an electric bulb mounted on the outer end of the innermost tube, means whereby the telescoped tubes are caused to move to an extended or a retracted position, a reflector connected to the outer end of the innermost tube and arranged to form a partial closure for the enlarged bowl end portion of the outer tube, said reflector having an outwardly extending concave portion arranged to envelop a portion of the bulb, a flexible envelope of translucent material having one of its ends connected to the reflector and its other end connected to the enlarged bowl portion of the outer tube whereby said envelope forms a chamber around the tubes in their extended position when the reflector is moved outwardly from said enlarged bowl portion and folds into the enlarged bowl portion of the outer tube upon the retractive movement of the telescoped tubes, and the outwardly extending concave portion of the reflector being arranged to reflect some of the light from the bulb back into the envelope in its outwardly extended position.

2. An auto-signaling device comprising an outer tube having an enlarged bowl end portion, a plurality of tubes telescopically mounted for slidable movement back and forth within the outer tube, an electric bulb mounted on the outer end of the innermost tube, means whereby the telescoped tubes are caused to move to an extended and a retracted position, a reflector having an inner annular open end connected to the outer end of the innermost tube and spaced apart therefrom, a transparent signal globe connected to the periphery of the reflector and enclosing the bulb, a flexible envelope of translucent material having one of its ends connected to the inner open end of the reflector and its other end connected to the enlarged bowl portion of the outer tube whereby said envelope is respectively folded and unfolded by the retractive and expansive movements of the telescoped tubes and whereby the envelope forms a chamber around the tubes in their extended position, and said reflector having a concave interior reflecting wall extended outwardly to envelop a portion of the electric bulb whereby some of the light therefrom is reflected back into the chamber formed by the flexible envelope in its extended position.

LEO J. BINDER.
